UNITED STATES PATENT OFFICE.

EARL ALBERT BUSSOM, OF INDIANAPOLIS, INDIANA, ASSIGNOR TO THE WHEELER-SCHNEIDER CARBURETOR CO., OF INDIANAPOLIS, INDIANA, A CORPORATION OF INDIANA.

CARBURETOR.

Original application filed April 30, 1917, Serial No. 165,323. Divided and this application filed March 6, 1919. Serial No. 230,928.

To all whom it may concern:

Be it known that I, EARL A. BUSSOM, a citizen of the United States, residing at Indianapolis, in the county of Marion and State of Indiana, have invented a new and useful Carburetor, of which the following is a specification.

In many carburetors, especially of the horizontal type, there is a pronounced tendency for the gasoline to form a pool on the leeward side of the nozzle, which in horizontal carburetors usually projects vertically into the air passageway. The formation of this pool of gasoline is objectionable for many reasons.

It is the object of my present invention to avoid the formation of such a pool of gasoline.

I do this by providing on the leeward side of the fuel nozzle a boss having a stream line surface which is swept clean by the passing air, thus avoiding the pocketing which results in the formation of a pool.

This application is a division of my co-pending application Ser. No. 165,323, filed April 30, 1917.

The accompanying drawing illustrates my invention: Fig. 1 is a vertical central section through a horizontal type carburetor embodying my invention; Fig. 2 is a horizontal section through the nozzle and adjacent parts, taken on the line 2—2 of Fig. 1; Fig. 3 is a similar horizontal section on the line 3—3 of Fig. 1, but with the nozzle itself removed; Fig. 4 is a perspective view of the lower half of the Venturi tube, showing the shape of the pool-eliminating boss; and Fig. 5 is a transverse section on the line 5—5 of Fig. 3.

The carburetor shown has a number of details which are not in point in the present application, but are described and claimed in my co-pending applications Ser. Nos. 165,322 and 165,323, both filed April 30, 1917, of the second of which applications this present application is a division, as has been stated.

The carburetor has an air intake fitting 10 which is controlled by a choker valve 11, and from the intake fitting 10 the air passes horizontally through the Venturi tube 12

and past the throttle 13. A fuel nozzle 14 projects upward vertically into this horizontal air passage at substantially the restricted point of the Venturi tube 12. This fuel nozzle is of special form, set forth in my aforesaid co-pending applications, and is provided with a number of fuel outlet openings 15 and with an air inlet opening 16, and from the top of the fuel nozzle a passage 17 extends to certain idling jets 18; but these features are not essential to the present invention, and so they and their associated parts will not be described in detail.

In order to prevent the formation of a pool of fuel on the leeward or discharge side of the fuel nozzle in the Venturi tube, I provide a stream line boss 20 at the place where such pool would otherwise tend to form. This boss fits closely against the outer surface of the fuel nozzle on its leeward side, as is clear from Figs. 1, 2, 3, and 4, and gradually tapers off both vertically downward and laterally toward the center line to form a stream line surface which is swept clean of fuel by the passing stream of air so that no pool of fuel can collect. This boss 20 is preferably formed as an integral part of the Venturi tube 12, as is clear from Fig. 4, and in order to avoid sharp corners there is preferably a fillet 21 at the juncture of such boss with the inside surface of the Venturi tube, as is clear from Figs. 4 and 5.

By reason of this stream line boss, the eddying of the air stream around and behind the fuel nozzle is prevented. This avoids disturbance of such air stream and all the disastrous effects which follow such eddying, but particularly it avoids the formation of a pool of gasoline on the leeward side of the fuel nozzle.

I claim as my invention:

1. In a carburetor, the combination of a substantially horizontal mixing tube, a fuel nozzle projecting vertically thereinto, and a boss on the leeward side of and abutting against said fuel nozzle and provided with a stream line surface whereby the formation of a pool of liquid on the leeward side of the fuel nozzle is prevented.

2. In a carburetor, the combination of a

substantially horizontal mixing tube, a fuel nozzle projecting upward thereinto, and a boss formed on the inner face of said mixing tube and located on the leeward side of and against said fuel nozzle, said boss tapering off both laterally toward the center line thereof and downward so as to form a stream

line surface which is swept clean of fuel by the passing air stream.

In witness whereof, I have hereunto set my hand at Indianapolis, Indiana, this third day of March, A. D. one thousand nine hundred and nineteen.

EARL ALBERT BESSOM.
